E. B. THURSTON

ELECTROMAGNET

Filed Sept. 30, 1921

UNITED STATES PATENT OFFICE.

ERNEST B. THURSTON, OF TOLEDO, OHIO, ASSIGNOR TO THE HAUGHTON ELEVATOR & MACHINE CO., OF TOLEDO, OHIO, A CORPORATION OF OHIO.

ELECTROMAGNET.

Application filed September 30, 1921. Serial No. 504,457.

To all whom it may concern:

Be it known that I, ERNEST B. THURSTON, a citizen of the United States of America, residing at Toledo, Lucas County, Ohio, have invented new and useful Electromagnets, of which the following is a specification.

This invention relates to electromagnets.

This invention has utility when incorporated in alternating current electromagnets of the polyphase type.

Referring to the drawings:

Fig. 1 is a side elevation of an embodiment of the invention in a polyphase electromagnet; certain parts being broken away;

Fig. 2 is an end elevation of the electromagnet, diagrammatically indicating the arrangement of these stator coils; Fig. 3 shows various characteristic curves including the ones described in this specification; and Fig. 4 is a detail view on an enlarged scale showing the laminated plunger in section and the taper thereof as extending only partially there along.

The structure is shown as embodying a housing 1 carrying therein laminated poles 2 in a ring form. About these poles 2 are wound a plurality of groups of coils 3, 4, 5, adapted to be connected to a three phase circuit. These coils have their axes extending inwardly to intersect each other and the core axis, and the windings of these coils are at an angle to the plane of the series of the poles as well as at an angle to radii from the core to said poles.

Concentric of this housing 1 is disposed plunger 6 having a main or major laminated plunger or core portion 7 with a taper portion 8 providing an air gap which is larger than that provided by an untapered core as to the poles 2 at the initial pull position for drawing this non-rotary core 7 from its normal position of rest into the region of the transverse field developed by the annular series of longitudinally extending windings. The respective turns of the windings do not encircle the core 7, but are in regions lying between radial planes extending axially of the core 7.

The plunger 6 is connected by link 9 to lever 10, which as thus rocked is effective through adjustable length link 11, to force brake shoe levers 12, 13, free of elevator brake drum 14, against the resistance of

spring 15, adjustable by rod 16. A base 17 may carry the structure, and stop 18 may be adjusted to limit the rocking of the lever 13. The spring 15 accordingly normally acts to hold the core 7 withdrawn from the region of the poles 2.

The magnetic pull of the core 7 is non-rotary. The core movement is normal to the plane of the coils. The successive coils in such a series are so wound as to establish a rotating field. As the plunger 6 is drawn to have its enlargement or core 7 move into the field of the flux generated by the coils 3, 4, 5, the leakage is reduced and the air gap area is increased. As the plunger gets into central position the forces acting upon it are balanced. There are no inductors carried by the plunger and the plunger in its design operates without any appreciable expenditure of energy tending to establish torque. The taper or reduction 8 in diameter of the core 7, while lengthening the air gap, also lessens the increase of the effective air gap area so that the increase in air gap area as the plunger is pulled into the core or stator which carries the coil, is out of direct proportion to the throw of said plunger.

The pull of this electromagnet is continuous due to the rotating field. Accordingly, there is no tendency to chatter, howl, or create other noise. In fact the pull and holding action of this magnet is quiet even when compared with direct current magnets, with possibilities for desirable design thereover. With the ordinary type of electromagnet and with the type of this disclosure with a straight cylindrical plunger and a straight cylindrical stator, the pull initially is greater than with the tapered plunger. As in this tapered construction the tapered portion remains in the influence of the field, there is increase in the final holding pull over the final holding pull in the ordinary type of electromagnet and over the final holding pull in the straight cylindrical plunger and straight cylindrical core type of structure of this disclosure. The curve 19 shows the influence of the core 7 with the taper 8 wherein the distance traveled is shown as abscissae and the pull is shown as ordinates (Fig. 3), as compared with the curve 20 which shows the pull and distance characteristic of an electromagnet in which the plunger does not have a taper. The tapered portion

8 is approximately only 25% of the portion 7 in the showing in Fig. 4. The taper can be made uniform for the full entrance of the core into the field, thereby taking the 5 hump out of the curve 19 and producing curve 21.

Instead of the normal concave curve 20, which is the characteristic of the usual alternating current type of electromagnet, it 10 is possible to obtain a characteristic as shown by the curve 19 in the type of electromagnet as herein disclosed, or even down to constant straight line pull may be produced in a quiet alternating current magnet of the 15 polyphase type. In the form of the curve 19, there is thus simply produced a slowing up in the pull action near the end of the stroke, which may be of material worth, not only in taking shock off the structure 20 and in quieting the brake operation, when a brake is controlled, but this slowing up may be gaged as to the spring 15 so that this spring may approximate dash pot co-operation in receiving and neutralizing any ham- 25 mer action adjacent the end of the plunger stroke.

The curve 20 is developed as from a non-sealing operation, and the range of the core reciprocation may be, say from line 22 as 30 outer limit of the stroke to line 23 against a stop. For a given magnet and voltage impressed, a stronger spring may be installed, and the pull may thus more closely approximate neutralizing the spring action 35 at the end of the stroke.

What is claimed and it is desired to secure by Letters Patent is:

1. The combination with a hollow core of 40 windings disposed on said core, a polyphase electric current supply for the windings for the production of a rotating magnetic field, and a plunger magnetized to effect relative movement into position within said core, said windings having the planes of the 45 wraps of said windings extending parallel to the line of direction of the plunger movement.

2. The combination with a hollow cylindrical core of windings disposed on said core, 50 a polyphase electric current supply for the windings for the production of a rotating magnetic field, and a plunger magnetized to be pulled into position within said cylindrical core providing a non-sealing air-gap 55 between said plunger and core, said windings having the planes of the wraps of said windings extending parallel to the line of direction of the plunger travel.

3. The combination with a hollow core of 60 converging windings disposed on said core, a polyphase electric current supply for the windings for the production of a rotating magnetic field, and a cylindrical plunger magnetized to effect relative pulling into 65 position within said hollow core.

4. The combination of a magnetic core, a relatively non-rotating plunger, and a winding wound on said core for the production of a magnetic field for effecting throw between the core and plunger, said core and plunger being dissimilarly configured on their opposing magnetic faces to provide a variable air gap therebetween.

5. The combination of a magnetic core, a relatively non-rotating plunger, and an alternating electric current winding wound on 75 said core for the production of a magnetic field for effecting throw between the core and plunger, said core and plunger providing in operative position a non-sealing 80 variable air gap.

6. The combination of a magnetic core, a relatively non-rotating plunger, and a winding wound on said core for the production of a magnetic field for effecting throw 85 between the core and plunger, said core and plunger being provided with mounting and directing means in inoperative position determining an air gap distance therebetween and in operative position having said same 90 air gap distance as a maximum between the same core and plunger.

7. The combination of a magnetic core, a relatively non-rotating plunger, and an alternating electric current winding wound 95 on said core for the production of a magnetic field for effecting throw between the core and plunger, said core and plunger providing at a position of rest in operative 100 position a variable air-gap extending in the direction of the line of throw.

8. The combination with a magnetic core having converging poles having faces, of a polyphase winding wound on said core for the production of a magnetic field, and a 105 relatively reciprocable non-rotating plunger magnetized to be moved along past portions of said pole faces.

9. The method of controlling a plunger as to its core of an alternating current 110 solenoid having a tapered portion and a straight portion, which comprises establishing a rotating magnetic field by supplying a polyphase current thereto, having the tapered portion within the influence of said field and the straight portion beyond the influence of said field when the plunger is in its inoperative position, and directing shifting to bring the plunger into a magnetically balanced position of rest in said field.

10. The method of controlling movement 115 between the plunger and core of an alternating current solenoid which comprises establishing a rotating magnetic field between faces of said plunger and core, directing a plunger to increase effective air gap area as acted upon in traveling relatively into said field, and modifying said air gap effective area as determined by directly opposing faces of said plunger and core to 120 125 130

depart from the direct travel proportion increase.

11. The combination of a magnetic core, a relatively non-rotating plunger, and an 5 alternating electric current winding wound on said core for the production of a magnetic field for effecting throw between the core and plunger, said plunger having a maximum magnetic field position and clearance as to said core in the throw direction 10 to, at and beyond said position.

12. The combination of a magnetic core, a relatively non-rotating plunger, and an 15 alternating electric current winding wound on said core for the production of a magnetic field for effecting throw between the core and plunger, there being an air gap between said core and plunger permitting balanced positioning of said plunger in 20 non-sealing position in said field.

13. The combination of a magnetic core, a relatively non-rotating plunger, and an 25 alternating electric current winding wound on said core for the production of a magnetic field for effecting throw between said core and plunger, said winding comprising a plurality of exciting coils, there being an air gap between faces of said core and plunger having in inoperative position an

effective area as determined by directly opposing portions of said faces, which area is automatically increased toward operative position.

14. The combination of a magnetic core, a relatively non-rotating plunger, and an 30 alternating electric current winding wound on said core for the production of a magnetic field for effecting throw between said core and plunger, there being an air gap between said core and plunger having opposing 35 faces in inoperative position to provide an effective area which is automatically increased toward operative positions, said increase in area departing from direct proportion with said throw.

15. The combination of a magnetic core having an annular series of radially directed poles, a polyphase winding on said poles for the production of a rotating magnetic field, and a plunger mounted concentrically 50 with the poles and in operative position having a taper face opposing said poles and spaced at different distances therefrom at a position of rest, the greater distance portion first entering the field in throw operation.

In witness whereof I affix my signature.
ERNEST B. THURSTON.
